[57] CLAIM

The ornamental design for a storage box, as shown and described.

DESCRIPTION

FIG. 1 is a perspective view showing the top, front end, and right side of a storage box embodying my new design;

FIG. 2 is a left side elevational view thereof;

FIG. 3 is a rear end elevational view thereof;

FIG. 4 is a bottom plan view thereof;

FIG. 5 is a view similar to FIG. 1 but showing the entry panel in open position;

FIG. 6 is a top plan view of the cover blank, shown separately for clarity of illustration, the bottom plan view being a mirror image; and,

FIG. 7 is a top plan view of the box blank, shown separately for clarity of illustration, the bottom plan view being a mirror image.
